T. J. SHUMATE,
EMBRYOTOMY DEVICE,
APPLICATION FILED AUG. 23, 1920.

1,397,461.

Patented Nov. 15, 1921.

Fig. 1.

UNITED STATES PATENT OFFICE.

THOMAS J. SHUMATE, OF WASHINGTON, DISTRICT OF COLUMBIA.

EMBRYOTOMY DEVICE.

1,397,461.

Specification of Letters Patent.

Patented Nov. 15, 1921.

Application filed August 23, 1920. Serial No. 405,491.

To all whom it may concern:

Be it known that I, Dr. THOMAS J. SHUMATE, a citizen of the United States, residing at Washington, District of Columbia, 5 have invented certain new and useful Improvements in Embryotomy Devices; and I do hereby declare the following to be a full, clear, and exact description of the invention, such as will enable others skilled 10 in the art to which it appertains to make and use the same.

The present invention relates to embryotomy devices, and aims to provide a novel and improved appliance for veterinary 15 obstetrical purposes.

Another object of the invention is the provision of such a device constructed and arranged to be grasped and manipulated by one hand, and including forceps or tongs 20 that can be manipulated by the hand for opening same and applying them to or closing them upon the fetus, and then clamped or set, to enable the delivery to be made.

A further object is the provision of such 25 a device having novel means for mounting and operating the forceps or tongs.

A still further object is the provision of such a device to which straps can be attached to be wrapped or wound around the 30 arm, or otherwise used for conveniently assisting the hand in pulling the device.

It is also an object of the invention to provide such a device, which is simple and inexpensive in construction and manufacture. 35

With the foregoing and other objects in view, which will be apparent as the description proceeds, the invention resides in the arrangement and construction of parts hereinafter described and claimed, it being understood that changes can be made within the scope of what is claimed without departing from the spirit of the invention.

The invention is illustrated in the accompanying drawing, wherein:—

Figure 1 is a plan view of the device as held in the hand, showing the straps applied to the arm.

Fig. 2 is an enlarged plan view, showing 50 the body or case and other portions in section.

Fig. 3 is a rear end view of the device.

Fig. 4 is a plan view of a modified form of tongs or forceps.

55 In carrying out the invention, there is provided a body or case 6, constructed of

sheet metal or other suitable material and of a size to be readily grasped and surrounded by the hand, the front and rear ends of said case being open, and a pair of forceps 60 or tongs 7 extend forwardly from within the case, and are pivotally connected, as at 8, at their point of crossing adjacent to the forward end of the case. Said tongs or forceps have arms 9 extending rearwardly 65 beyond the pivot 8 into the case, and connected by pivots 10 with the forward ends of crossed bars 11 and 12 within the case engaging a bolt or similar member 13 at their point of crossing, said bolt being preferably 70 riveted or otherwise secured to one side of the case, and extending through the opposite side. The bar 11 is rigidly secured to the case, by one or more rivets 14, or the like, engaging through said bar and opposite 75 sides of the case, and a toggle or lazy-tong connection is thus provided between the forceps or tongs 7 and bars 11 and 12. A wing or thumb nut 15 is screw threaded on the bolt 13 and bears against a washer 80 or spacer 16 extending through the corresponding side of the case and bearing against the bar 11, whereby said nut can be tightened and loosened by the fingers of the hand. 85

In grasping the device, the case or body 6 is held in the hand, with the first and second fingers hooked across the forward end of the case, and the third finger extending rearwardly through a finger ring 17 secured 90 to one edge of the case, and the thumb and little finger can be bent under the case, as seen in Fig. 1, thereby obtaining a good hold on the case. The parts of the case are covered by the hand, to prevent injury therefrom, during the operation, and the device 95 is readily inserted and withdrawn in the hand.

By loosening the nut 15, it is an easy matter to separate the tongs 7 and to then 100 close them upon the fetus, after which the nut 15 is again tightened, thereby frictionally clamping the bars 11 and 12 within the case 6 and securely holding or setting the tongs or forceps 7 in place, to prevent 105 them from opening.

In order to assist the hand in pulling the device, the rear ends of the bars 11 and 12 have loops 18 or equivalent means extending from the rear end of the case 6, for the connection of straps 19, or the like, which can be readily attached to the loops 18 by the 110

hand, after the device has been applied. The straps 19 can then be wrapped in opposite directions helically around the arm, as seen in Fig. 1, and the terminals thereof 5 opposite to the case 6 connected by a buckle 20 or otherwise, after passing same around the neck, as at 21, thereby anchoring the straps to the arm and body, to prevent slipping, or, the straps can be used otherwise 10 for pulling the device.

As shown in Figs. 1 and 2, the tongs 7 have hooks 22 for use with a dead fetus, and, as shown in Fig. 4, the tongs have 15 spoons or concaved jaws to embrace a live fetus, without injuring same.

Having thus described the invention, what is claimed as new is:—

1. An embryotomy device comprising a member of a size to be grasped and surrounded by the hand, said member having a forward end across which the fingers can be hooked, tongs or forceps connected to said member and extending from said forward end thereof and arranged to be opened and 25 closed by the hand, and means operable by the hand for holding said tongs or forceps in position.

2. An embryotomy device comprising a case of a size to be grasped and surrounded 30 by the hand, said case having a forward end across which the fingers can be hooked, a pair of tongs or forceps extending from within the case beyond said end of the case and connected to the case, said tongs or forceps 35 being arranged to be opened and closed by the hand, and means operable by the hand for holding said tongs or forceps in position.

3. An embryotomy device comprising a member of a size to be grasped and surrounded 40 by the hand, a pair of tongs or forceps having a toggle connection with said member and adapted to be readily opened

and closed by the hand, and means for clamping said toggle connection after the tongs or forceps have been set to hold the 45 tongs or forceps in place.

4. An embryotomy device comprising a case of a size to be grasped and surrounded by the hand, crossed bars within said case, a pivot member for said bars at the point 50 of crossing, means on said member for clamping said bars and operable by the hand, and crossed and pivoted tongs or forceps projecting from the case and having arms extending within the case and 55 pivotally connected with said bars to provide a toggle connection.

5. An embryotomy device comprising a case, adapted to be grasped by the hand, a pair of tongs or forceps extending from 60 within the case beyond one end thereof, and adapted to be opened and closed by the hand, portions extending from within the case from the other end thereof for the connection of straps and connected to said tongs or 65 forceps and case, and means for holding said tongs or forceps in place when swung to position.

6. An embryotomy device comprising a case, crossed bars within the case having 70 loops extending from one end thereof for connection of straps, a pivot member for said bars at the point of crossing, means on said member for clamping the bars, and a pair of crossed tongs or forceps extending 75 from the other end of the case, said tongs or forceps being pivoted together at their point of crossing and having arms extending within the case and pivotally connected to said bars to provide a toggle connection. 80

In testimony whereof I have signed my name to this specification.

THOMAS J. SHUMATE.
